UNITED STATES PATENT OFFICE

159,344

PAIR OF SUN GLASSES

Alfred S. Jonaitis, New York, N. Y.

Application June 8, 1949, Serial No. 3,109

Term of patent 7 years

(Cl. D57—1)

To all whom it may concern:

Be it known that I, Alfred S. Jonaitis, a citizen of the United States, residing at New York city, county and State of New York, have invented a new, original and ornamental Design for a Pair of Sun Glasses, of which the following is a specification, reference being had to the accompanying drawing, forming part thereof, and in which:

Figure 1 is a front perspective view of a pair of sun glasses, showing my new design.

Figure 2 is a fragmentary central vertical section, taken on the line 2—2 of Figure 1.

Figure 3 is a fragmentary central vertical section, taken on the line 3—3 of Figure 1.

The essential features of my design reside in the parts shown in full lines.

I claim:

The ornamental design for a pair of sun glasses, substantially as shown and described.

ALFRED S. JONAITIS.
